F. E. FISHER.

STARTER FOR INTERNAL COMBUSTION ENGINES.

APPLICATION FILED FEB. 24, 1919.

Patented July 13, 1920.

UNITED STATES PATENT OFFICE.

FRANK E. FISHER, OF DETROIT, MICHIGAN.

STARTER FOR INTERNAL-COMBUSTION ENGINES.

1,346,598.

Specification of Letters Patent. Patented July 13, 1920.

Application filed February 24, 1919. Serial No. 278,623.

To all whom it may concern:

Be it known that I, FRANK E. FISHER, a citizen of the United States, residing at Detroit, county of Wayne, State of Michigan, have invented a certain new and useful Improvement in Starters for Internal-Combustion Engines, and declare the following to be a full, clear, and exact description of the same, such as will enable others skilled in the art to which it pertains to make and use the same, reference being had to the accompanying drawings, which form a part of this specification.

My invention relates to a starter for internal combustion engines, being especially designed for use upon the Ford type of motor driven car.

It is well known that the available space on a Ford automobile for the installation of an engine starter is very limited and it is desirable and equally necessary that the starting device employed shall not interfere with the working parts of the motor or vehicle, and shall at the same time be readily accessible for inspection and repairs.

Heretofore devices usually employed on installation of this character have been of the "chain driven type" of construction, but it has been found in practice that due to carelessness in the adjustment of the spark control the chain is sometimes broken through "backfiring" of the engine;—it is therefore the object of the present invention to dispense with the chain drive and to attach the case of the starting unit directly to the large timing gear case of the engine;—mounting upon the shaft of the generator a pinion in mesh with the large time gear, which in turn meshes with the small time gear on the crank shaft of the engine. The crank shaft of the engine may thus be "turned over" upon energizing the starting unit, the usual driving chain connection with its resulting objectionable features being thereby eliminated.

With the foregoing and other objects in view, which will appear as the description proceeds, the invention resides in the combination and arrangement of parts, and in the details of construction hereinafter described and claimed, it being understood that changes may be made in the precise embodiment herein disclosed without departing from the spirit of the invention.

In the accompanying drawings:—
Figure 1 is a fragmentary side elevation

of an engine of the "Ford" type showing the engine starting unit installed thereon.

Fig. 2 is a fragmentary end elevation of the same.

Fig. 3 is a sectional view on line 3—3 of Fig. 1, showing the starting unit case attached to the case of the large time gear and also the driving gear connection between the generator shaft of the starting unit and the large time gear of the engine.

Fig. 4 is a fragmentary side elevation partly in section (taken on line 4—4 of Fig. 2) showing the timing gears and the gears of the starting unit with which they co-operate.

Referring now to the letters of reference placed upon the drawings,

A, denotes an internal combustion engine,—that shown being of the "Ford" type of motor. B, indicates the case of the starting unit secured to the case C of the large time gear by bolts D.

E, indicates the shaft of the motor and F a pinion on said shaft in mesh with a gear G. H, is a pinion on the shaft of the gear G, in mesh with a gear I, on the generator shaft J. K, denotes a pinion on the generator shaft in mesh with the large time gear L, mounted on the cam shaft M, which in turn operates the valve push rods N of the engine. P, denotes a small time gear mounted upon the engine crank shaft Q, in mesh with the large time gear L.

The usual case of the large time gear employed on the Ford engine is divided along the line R, and to this is secured the gear case of the starting unit by the bolts D, previously indicated.

To "turn over" the engine crank shaft, the starting unit is first energized in the usual manner, thereby actuating the train of gears connected with the pinion K on the generator shaft, which in turn operates the large time gear L, of the cam shaft, in mesh with the small time gear P on the crank shaft of the engine,—thereby causing the latter to rotate that the engine may operate under its own power in a manner well understood.

Having thus described my invention, what I claim is:

1. In a device of the character described, the combination of an internal combustion engine, a time gear casing, a time gear mounted on the cam shaft of the engine, a gear mounted on the crank shaft of the en-

gine and meshing with the time gear and an electric starter and generator unit comprising a casing secured to the time gear casing at one side thereof, a generator arranged within the latter casing, a pinion mounted on the generator shaft and meshing with the time gear, a motor mounted within the casing of said unit, a pinion mounted on the motor shaft and a train of gearing also arranged within the casing of the said unit and meshing with the pinion of the motor shaft and connecting the same with the generator shaft.

2. In a device of the class described the combination of an internal combustion engine, a divided time gear casing open at one side, a time gear arranged in the said casing and mounted on the cam shaft of the engine, a gear mounted on the crank

shaft of the engine and meshing with the time gear, and an electric starter and generator unit comprising a casing open at the inner side and secured to the time gear casing at the open side thereof, a generator arranged within the casing of the said unit, a pinion mounted on the generator shaft and meshing with the time gear, a motor arranged within the casing of the unit, a pinion mounted on the motor shaft and a train of gearing located within the casing of the unit and connecting the pinion of the motor shaft with the generator shaft.

In testimony whereof, I sign this specification in the presence of two witnesses.

FRANK E. FISHER.

Witnesses:

S. E. THOMAS,
EDWIN R. MONNIG.
